UNITED STATES PATENT OFFICE.

JOHN S. AFFLECK, OF BROOKLYN, (GREEN POINT STATION,) NEW YORK.

PACKING-RING FOR BOILER-TUBES.

SPECIFICATION forming part of Letters Patent No. 229,070, dated June 22, 1880.

Application filed December 26, 1879.

To all whom it may concern:

Be it known that I, JOHN S. AFFLECK, of Brooklyn, (Green Point Station,) in the county of Kings and State of New York, have invented a new and useful Improvement in Metallic Packing-Rings for the Joints of Tubular Boilers, of which the following is a specification.

Figure 1 is a sectional view of the improvement shown as applied to a tube-connection. Fig. 2 is a side view of one of the packing-rings. Fig. 3 is a cross-section taken through the line $x-x$, Fig. 2.

Similar letters of reference indicate corresponding parts.

The object of this invention is to furnish packing-rings so constructed that they will adjust themselves to any imperfections in their seats, and will melt should the boiler become unduly heated.

I will describe the improvement as applied to the tube-connections of a Root's tubular boiler, but do not wish to limit myself to that application, as my improvement may be used with advantage in various other places.

A represents a boiler-tube connection, the rims B of which are connected with apertures in the boiler end plates, attached to the ends of the tubes. Around the rim B is formed a flange or shoulder, C, the face of which is grooved or recessed to receive the packing-ring.

D is the body of the packing-ring, which is interposed between the recessed shoulder C and a corresponding recess in the end plate. 35 The packing-ring D is made of a soft metal, and has V-shaped lips E formed upon its opposite sides. With this construction, when the connection A is secured in place, the ribs E, being made thin, will yield to any roughness in the seats, and will be pressed into any depressions in the said seats, so as to make a close joint. 40

With this packing, should the water get low in the boiler and the boiler become unduly heated, the packing-rings will melt and allow steam to escape and give warning before the overheating has reached a dangerous point. 45

I am aware that soft metal has been heretofore used in packing-rings; but 50 What I claim as new and of my invention is—

A soft-metal packing-ring having a body, D, provided with a lip, E, on each side, in combination with a boiler-tube connection having a rim, B, with the grooved flange C, as and for the purpose specified. 55

JOHN S. AFFLECK.
